Primary Examiner — Samantha Q Lawrence*Assistant Examiner* — Melissa Adriane Santos(74) Attorney, Agent, or Firm — The Belles Group, P.C.(57) CLAIM

We claim the ornamental design for a light fixture, as shown and described.

DESCRIPTION

FIG. 1 is a perspective view of the claimed design; FIG. 2 is a front view of the claimed design shown in FIG. 1; FIG. 3 is a rear view of the claimed design shown in FIG. 1; FIG. 4 is a side view of the claimed design shown in FIG. 1; FIG. 5 is another side view of the claimed design shown in FIG. 1; FIG. 6 is a top view of the claimed design shown in FIG. 1; and, FIG. 7 is a bottom view of the claimed design shown in FIG. 1.

The broken lines shown in FIGS. 1-7 illustrate portions of the light fixture that form no part of the claimed design.

1 Claim, 6 Drawing Sheets(56)
